T. W. Harvey,

Making Wrought Nails,

Patented Jan. 24, 1832

Thomas W. Harvey
Inventor

The Vehicle referred to in the Letters Patent and making part of the same containing a description in the words of the said Thomas W. Harvey, himself of his Improvement in the Machine for making wrought nails.

Be it known that I Thomas W. Harvey of James town Schenectady County State of New York have made a new and useful improvement in the Machine for making wrought nails which is described as follows. The Machine may be made wholly of cast and wrought iron and steel, or the frame may be made of wood.

The frame marked A, in the annexed drawing, is made about ten feet long, two feet wide, and two and a half feet high, having an opening B, left in the centre thereof extending nearly its whole length to admit the rollers C, C, hereafter to be described. The swaging rollers or die plates D, D, passing in or rolling out the nails, are made of steel ten inches in diameter, and as thick as the required nail. The circumference of each of said swaging rollers or die plates, is divided into two or more or less equal parts, according to the length of the nail to be rolled or swaged, and each division on the periphery of the swaging rollers or die plates, and the corresponding one on the opposite roller or plate are to be filed away and shaped, or indented, in such a manner, that when they come together during the revolution of the swaging rollers or die plates, they will form the head or nail in exactly the shape of the nail to be rolled or swaged therein; and there are also the same number of chisels E, E, E, as there are divisions, mounted into the peripheries of the swaging rollers or die plates to cut the nail from the rod as fast as rolled; said chisels coming together with their edges, as the swaging rollers or die plates revolve. The swaging rollers or die plates D, D, are secured firmly on the ends of the arms, F, F, hereafter to be described, by collars G, G, and G, G, having screws H, H, H, passing through the collars G, G, and the swaging rollers or die plates D, D, into the fixed rollers K, K, the collars G, G, being movable, thus collars being kept in the swaging rollers or die plates forward and true in a vertical position, are able to make

the shafts. The swaging rollers or die plates are placed across the ends of the frame upon revolution in a vertical position opposite and against each other as shown in the drawing. Side Rollers - on the sides of the swaging rollers or die plates under where their peripheries meet are placed two rollers C, C, at right angles to them revolving also in a vertical position with their peripheries nearly in contact leaving just space enough to form the size of the nail. The swaging rollers or die plates forming the right hand as before described. These rollers are four feet in diameter, the peripheries of which are of cast wrought iron or steel and may be plain or indented. They are supported and turned on a set of standards T, T, secured to the frame by screws D, D, and are brought parallel to or further from each other as a center may require by the tempering screws N, N, bearing against the edges of the standards T, T, on the side of one the roller C is formed a cylindrical row of pegs or cast O, into which the pinion P, is indented in diameter placed on the end of axle A, mounted and by which the rollers C, C are turned.

Stages and cogwheels. On each side of the frame and parallel with each other are placed two sets D, D, supporting and turning with their bearings or journals in openings in the heads of standards T, T, T, T. On the ends of said axle, over the centre of the frame, are placed the swaging rollers or die plates as before described, and at the other ends are secured the cogwheels.

Size ten and a half inches in diameter, mounting into each other. The stand arms are all regulated by tempering screws, those of the centre of the frame by the screws T, T, bearing on the swaging rollers or die plates. U, U are cavities in the top of the frame containing water, in which the outer edges of the swaging rollers or die plates revolve, to prevent their becoming heated. The machine is operated by steam, manual or any known power applied to the shaft A, on which is represented a crank in the drawing. The rods of iron upon which the nails are swaged or rolled are slit of a proper size and heated, then passed perpendicularly through an iron tube or guide rod set along the machine below on the swaging roller die plates and there swaged rolled or formed into nail of any shape required.

The proportions and dimensions of the several parts of the before described machine may be varied to suit the different kinds and sizes of nail required.

609X
the proportion of the wire rollers may also be varied.

What I particularly claim
as my improvement in the before described machine for making wrought
wire are the wire rollers, C, C, and the general arrangement of the gearing
thereon as claimed in the swinging rollers or die plates.

In testimony that the foregoing
is a true description of my said improvement, I have hereunto sub-
scribed my name before two witnesses this 31st day of January 1838.
